UNITED STATES PATENT OFFICE.

WILLIAM F. SHAW, OF PUEBLO, COLORADO.

CLASP FOR PLATES OR REMOVABLE BRIDGES.

1,293,950.

Specification of Letters Patent. Patented Feb. 11, 1919.

Application filed September 16, 1918. Serial No. 254,294.

To all whom it may concern:

Be it known that I, WILLIAM F. SHAW, a citizen of the United States, residing at Pueblo, in the county of Pueblo and State 5 of Colorado, have invented a new and useful Clasp for Plates or Removable Bridges, of which the following is a specification.

The subject of this invention is a clasp for plates or removable bridges. 10 The main object of the invention is the provision of a clasp which may be readily placed in position to embrace a tooth and removed therefrom.

Another object of the invention is the 15 provision of a clasp which may be firmly anchored to the solder or vulcanite rubber.

Another object of the invention is the provision of means for detachably securing the clasp to a tooth.

Another object of the invention is the provision of means for retaining the clasp in 20 position on a tooth so that the same may not be pressed down against the gum in biting.

The invention also contemplates generally 25 improving the construction and enhancing the utility of clasps of this character.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made 35 within the scope of what is claimed without departing from the spirit of the invention.

A practical structure for carrying out the invention is shown in the accompanying drawings, wherein:

40 Figure 1 is a perspective view of a strip prepared in accordance with the invention and ready to be bent into a clasp;

Fig. 2 is a perspective view of a clasp constructed in accordance with the invention;

Fig. 3 is a perspective view of a clasp with a supporting plate in place thereon;

Fig. 4 is a view in front elevation of a removable bridge constructed with clasps 50 in accordance with the invention;

Fig. 5 is a plan view of the same;

Fig. 6 is a section taken on the line 6—6 of Fig. 5;

Fig. 7 is an enlarged detail sectional view 55 showing the locking of the solder to the clasp;

Fig. 8 is a section on the line 8—8 of Fig. 4.

Referring to the drawings by numerals of reference:

In carrying out the invention there is provided a strip of suitable metal 1, which has the requisite qualities of resiliency and hardness, and which is capable of resistance to deterioration, and this strip is curved 65 transversely to conform to the contour of a tooth as seen most clearly in Fig. 1. Apertures 2 are drilled in the strip 1, and a space longitudinally thereof, and these apertures are countersunk or reamed out on the 70 inner or concave side of the strip to form a locking means as will be hereinafter described.

Slits are formed in each longitudinal edge 75 of the strip 1, about midway between the ends thereof, and these slits converge inwardly. The portions 3, formed by the slits at one edge, are bent outwardly to form prongs. The portion 4, contained between the slits at the other edge is bent outwardly to form the trapezoidal projection, as seen most clearly in Fig. 2. The strip is 80 bent longitudinally, as seen in Figs. 2 and 3, to embrace a tooth.

The prongs 3 are adapted to pass through 85 slits or apertures formed in a plate 5, and to be bent back upon the plate to clamp the same in position upon the strip or clasp 1. The plate 5 is formed of thin malleable 90 metal and is bent to project inwardly above the clasp so as to be in position to rest in the cusp of the tooth and support the clasp against downward pressure against the gum. The inwardly bent portion of the plate 5 is 95 preferably built up, reinforced and thickened by solder so that the same may resist the action of biting. This building up of the plate 5 is preferably had after the strip 1 has been bent to embrace the particular tooth to which it is to be fitted, and the plate 5 has also been bent to conform to the 100 cusp of the tooth.

When the clasps have been prepared as just described, the impression and bite are taken and the artificial teeth are attached to the clasps by solder or vulcanite rubber. The solder or vulcanite rubber will flow about the outwardly bent portion 4, and this portion will act to anchor the clasp to the solder. The solder or rubber will also 105 flow through the apertures 2, and will spread into the countersunk portions, there- 110

by locking the solder or rubber to the clasp, as seen most clearly in Fig. 7.

Because of the outturned portion 4, a gap or indentation is made in the lower edge of 5 the clasp which permits the clasp to be drawn well down toward the gum so that, when the plate or bridge is prepared as just described, an aperture of the clasp will be found to be located on the labial side of the 10 tooth, and at a central position on that side of the tooth.

For the purpose of detachably locking the clasp in position upon the tooth, the 15 clasp is placed in position and a drill inserted through the aperture to mark the point on the tooth over which the aperture falls. The clasp is then removed and a slight cavity formed in the tooth, preferably with a number six drill, by drilling into 20 the tooth until the head of the drill is about half buried. A ball 7, of suitable metal, is then cemented into the cavity, being half buried therein. The resiliency of the clasp will allow the clasp to spring over the ball 25 7, and the projecting portion of the ball will enter the countersunk portion of the aperture 2, as seen most clearly in Fig. 8, to detachably secure the clasp in place.

The ball just described is not an essential 30 portion of the structure and may be left out if desired. It is also possible to omit the plate 5, should the operator wish, and in such case the prongs 3 serve to anchor the clasp to the solder or rubber.

From the foregoing it will be evident that 35 clasps of various sizes may be supplied and that, with little additional bending, such clasps may be made to fit any size tooth.

Having thus described my invention, what 40 I claim as new and desire to secure by Letters Patent, is:—

1. A clasp for plates or removable bridges, including a metallic strip bent to conform

to the contour of a tooth, the said strip provided with a countersunk aperture.

2. A clasp for plates or removable bridges, including a metallic strip bent to conform 45 to the contour of a tooth, the said strip provided with a countersunk aperture, and an element engageable with the aperture for detachably securing the clasp to a tooth.

3. A clasp for plates or removable bridges including a metallic strip bent to engage a tooth, there being an anchoring tongue struck from the lower edge of the strip and 55 defining an opening permitting the clasp to be brought down close to the gum without pressing on the gum.

4. A clasp for plates or removable bridges, including a metallic strip adapted to engage 60 a tooth, there being an anchoring tongue struck from the strip, and there being a bendable retaining prong struck from the strip in spaced relation to the tongue.

5. A clasp for plates or removable bridges, 65 including a metallic strip adapted to embrace a tooth; and a plate comprising angularly disposed parts, one of which extends rearwardly, the other of which overlaps the strip, there being a prong struck 70 from the strip, the prong extending through the last specified part of the strip and being clenched thereon.

6. A clasp for plates or removable bridges, 75 including a metallic strip adapted to embrace a tooth, the said strip provided with an aperture, and a ball adapted for attachment to a tooth and engageable with the aperture.

In testimony that I claim the foregoing 80 as my own, I have hereto affixed my signature in the presence of two witnesses.

WILLIAM F. SHAW.
